US0D1077069S

(12) **United States Design Patent** (10) **Patent No.:** **US D1,077,069 S**
(45) **Date of Patent:** **** May 27, 2025**

(54) **TOY**

(71) Applicant: **SHANTOU CITY CHENGHAI JINGWEI INDUSTRIAL CO., LTD.**,
Shantou (CN)

(72) Inventor: **Yutao Xu**, Shantou (CN)

(73) Assignee: **SHANTOU CITY CHENGHAI JINGWEI INDUSTRIAL CO., LTD.**,
Shantou (CN)

(**) Term: **15 Years**

(21) Appl. No.: **29/989,849**

(22) Filed: **Feb. 17, 2025**

(30) **Foreign Application Priority Data**

Jan. 7, 2025 (CN) 202530008707.6

(51) **LOC (15) Cl.** **21-01**

(52) **U.S. Cl.**

USPC **D21/468**; D21/787

(57) **CLAIM**

The ornamental design for a toy, as shown and described.

DESCRIPTION

FIG. 1 is a front, right and top perspective view of a toy, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the toy that form no part of the claimed design.

1 Claim, 8 Drawing Sheets
